UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

AIR-FEED CONTROL FOR ROCK DRILLS.

Application filed May 23, 1921. Serial No. 471,903.

To all whom it may concern:

Be it known that I, LEWIS C. BAYLES, a citizen of the United States, and a resident of Easton, Northampton County, State of Pennsylvania, have invented a certain Air-Feed Control for Rock Drills, of which the following is a specification accompanied by drawings.

This invention relates to fluid pressure rock drills of the hammer type having automatic rotation for the drill steel dependent upon the hammer piston, as for instance rifle bar rotation, as distinguished from independent rotation, but relates more particularly to automatic control for the feeding element which advances the machine.

This feeding element may be an air feed cylinder and piston or other fluid actuated device, and the objects of the invention are to enable the air feeding element to be automatically controlled by the rotation devices in accordance with or responsively to the resistance to rotation.

Various means may be devised for so controlling the feeding means in a rock drill of the type referred to without departing from the spirit of my invention as shown and described herein and defined in the appended claims, and I have illustrated one preferred form of the invention in the accompanying drawings in which—

Figure 1 is a vertical sectional elevation of a stope drill constructed in accordance with my invention;

Figure 2 is a horizontal sectional view on the line 2—2 of Figure 1 with the air feed controlling valve closed;

Figure 3 is a view similar to Figure 2 with the said valve open, and

Figure 4 is a transverse sectional view on the line 4—4 of Figure 1.

Referring to the drawings, only so much of the operative parts of a rock drill are shown as will serve to illustrate the invention, and those portions which can be shown diagrammatically for clearness are so indicated, as for instance the drill casing and the ports and passages therein.

The cylinder A is provided with the front head B containing the rotation sleeve C into which the drill steel D extends in the usual manner. A reciprocating hammer piston E of the valveless type is illustrated formed with a head F and a forwardly extending

reduced and fluted shank G extending 55 through the front cylinder bushing G' and having slidable but non-rotative engagement with the rotation sleeve C. A rearwardly extending piston shank H is formed with a reduced neck J and the cylinder is formed 60 with the supply passages K and L and the exhaust port O controlled by the hammer piston in the usual manner as well understood.

The cylinder is provided with the back 65 cylinder portion P containing a ratchet ring Q loosely held between a plate R and the head block S. A rifle bar T engages the piston shank H and is provided with a head U within the ratchet ring Q and the usual 70 spring pressed pawls V are adapted to engage the teeth of the ratchet ring Q and hold the rifle bar stationary as the piston moves in one direction thereby imparting rotation to the drill steel.

The throttle valve W mounted in the head block S and provided with the handle X controls the supply of motive fluid from the supply pipe Y to the percussive element and also to the feeding element which is shown 80 in this instance in the form of a cylinder Z on which the percussive element is mounted in any suitable manner as by means of the collar a, the parts forming the casing of the percussive element and the feeding element 85 being adapted to be held together by the usual side bolts b indicated in sectional view in Figures 2 and 3. The feed cylinder Z is provided with a piston c having a piston rod d in slidable but non-rotative engagement therewith. For this purpose the piston rod may be formed with the grooves e adapted to engage projections f at the rearward or lower end of the feed cylinder Z.

A claw foot g of any suitable construction 90 may be transversely pivoted at h to the end of the piston rod d.

In accordance with this invention, the actuating devices dependent upon the hammer piston for rotating the drill steel also 100 actuate a valve or other suitable device for controlling the air feed means automatically and responsively to the resistance to rotation. This may be accomplished by automatically opening an exhaust passage h in the head block S from the feed cylinder to the atmosphere at the exhaust port j in the back cylinder portion P, although it is un-

2
derstood that this exhaust passage and exhaust port may be arranged in any suitable location. An air feed controlling valve *k* having the heads *o* and *p* and the neck *q* may be mounted in the back cylinder portion *P* adjacent the ratchet ring *Q* in position to be actuated by a stop *r*, shown in the form of a radial arm extending from the ratchet ring *Q* opposite the head *o* of the valve *k*.

The valve *k* is normally maintained in closed position as by means of the spring *s* or other suitable device which is of sufficient strength to normally resist the thrust of the ratchet ring. A cap *t* having a vent *u* covers the portion of the back cylinder portion *P* forming the valve casing. As shown in Figure 2 the valve head *p* normally closes communication between the exhaust passage *h* and the exhaust port *j*, but upon a sufficient increase of the resistance to rotation to cause the stop or arm *r* on the ratchet ring to bear against the valve *k* with sufficient force to overcome and compress the spring *s*, the valve will be moved to open position as indicated, thus relieving the pressure in the air feed cylinder and reducing the feed. When the rotation again becomes normal the ratchet ring will permit the valve *k* to close and normal rotation and air feed will be resumed. The device operates automatically to control the air feeding element responsively to the resistance to rotation.

35 I claim:

1. In a rock drill of the hammer type, the combination of a cylinder and reciprocating hammer piston, operative devices co-operating with the hammer piston for automatically rotating the drill steel, means for feeding the machine forward, and means responsive to the resistance to rotation for automatically controlling the feeding means.

2. In a rock drill of the hammer type, the combination of a cylinder and reciprocating hammer piston, operative devices co-operating with the hammer piston for automatically rotating the drill steel, means for feeding the machine forward, and means actuated by the rotating devices responsively

to the resistance to rotation for automatically controlling the feeding means.

3. In a rock drill of the hammer type, the combination of a cylinder and reciprocating hammer piston, operative devices co-operating with the hammer piston, and including a rifle bar and ratchet and pawl device for automatically rotating the drill steel, means for feeding the machine forward, and means actuated by the ratchet and pawl device responsively to the resistance to rotation for automatically controlling the feeding means.

4. In a rock drill of the hammer type, the combination of rifle bar rotation for the drill steel, means for feeding the machine forward, and means controlled by the rifle bar and responsive to the resistance to rotation for automatically controlling the feeding means.

5. In a rock drill of the hammer type having slip rotation for the drill steel, the combination of means for feeding the machine forward, and means controlled by backward slip of the rotating devices for automatically controlling the feeding means.

6. In a rock drill of the hammer type, the combination of rifle bar rotation for the drill steel having a ratchet ring adapted to move upon increase of the resistance to rotation, means for feeding the machine forward, and a valve opposing the movement of the ratchet ring and connected to automatically control the feeding means in accordance with the resistance to rotation.

7. In a rock drill of the hammer type, the combination of rifle bar rotation for the drill steel having a ratchet ring adapted to move upon increase of the resistance to rotation, means for feeding the machine forward, a stop on the ratchet ring, and a valve mounted adjacent the ratchet ring and actuated by said stop, said valve controlling the feeding means, whereby the feed is automatically regulated in accordance with the resistance to rotation.

In testimony whereof I have signed this specification.

LEWIS C. BAYLES.
